US0D1100067S

(12) **United States Design Patent** (10) Patent No.: **US D1,100,067 S**
(45) Date of Patent: ** Oct. 28, 2025

(54) **TOY TRACK SECTION**

(71) Applicant: **MVW HOLDINGS, Inc.**, Bolingbrook, IL (US)

(72) Inventors: **Michael Valenta**, Naperville, IL (US); **Michael Wehrli**, Naperville, IL (US); **Olga Valenta**, Naperville, IL (US); **Michael Scheffki**, Downers Grove, IL (US); **Aaron Nelson**, Salt Lake City, UT (US); **Isabella Mae Esposito**, Salt Lake City, UT (US); **Edward Adam Packer**, Murray, UT (US); **Joshua Mihkel Gandy**, Saratoga Springs, UT (US)

(73) Assignee: **MVW HOLDINGS, Inc.**, Bolingbrook, IL (US)

(**) Term: **15 Years**

(21) Appl. No.: **29/974,498**

(22) Filed: **Nov. 22, 2024**

Related U.S. Application Data

(63) Continuation of application No. 29/853,424, filed on Sep. 15, 2022, now Pat. No. Des. 1,072,088.

(57) **CLAIM**

The ornamental design for a toy track section, as shown and described.

DESCRIPTION

FIG. 1 is a front, top, right-side perspective view of a toy track section;

FIG. 2 is a front view thereof;

FIG. 3 is a rear view thereof;

FIG. 4 is a top view thereof;

FIG. 5 is a bottom view thereof.

FIG. 6 is a right-side view thereof; and,

FIG. 7 is a left-side view thereof.

The broken lines in the drawings depict portions of the toy track section that form no part of the claimed design.
